UNITED STATES PATENT OFFICE.

MICHAEL LOPRETE, OF NEWARK, NEW JERSEY.

GATE.

1,231,763.

Specification of Letters Patent.

Patented July 3, 1917.

Application filed December 30, 1916. Serial No. 139,744.

To all whom it may concern:

Be it known that I, MICHAEL LOPRETE, a citizen of the United States, and a resident of Newark, county of Essex, and State of New Jersey, have invented certain new and useful Improvements in Gates, of which the following is a specification.

This invention relates to an improved gate and is designed to provide a gate that 10 gives way to a limited extent when an obstructed object hits it, whereby strain on the gate is minimized, its fastenings can be relieved of a breaking strain and the object encountering the barrier eventually stopped.

15 The gate is adapted for various locations and can be adapted to meet varying conditions, but it is particularly adapted for highways, such as toll gates or the gates used on bridges adjacent to a draw, to block 20 or prevent traffic from passing beyond a certain point while the draw is open. It has been the custom to make these bridges of toggle form and also of a form that swings on one end, the latter being the usual 25 form, and these are fastened in position by a fixed fastening means, and the gate being stiff, there is a rigid barrier provided. In such cases, particularly on the gates of ferry boats and on bridges, the fastening is provided by dropping a bar that is arranged 30 so that it slides on the gate into a depression or hole in the roadway, and this gives but small purchase, and when a vehicle not quite under control engages such barrier, 35 the strain is sufficient sometimes to break the fastening means or to pull it from its socket, and such broken or displaced fastening means removes all resistance and the barrier no longer acts to stop a moving vehicle.

40 My improved gate is fastened securely in place, the barrier portion being adapted to be distorted to a limited extent, the barrier being constructed with resilient and flexible members in its structure so that it yields, 45 thereby submitting the fastening means to a gradually increasing strain instead of to a sudden shock, thus minimizing the chance of breaking such fastening means and thereby providing a barrier not apt to open the 50 the way by reason of a breakage in its construction.

The invention further resides in a gate, the barrier of which can be constructed economically, the maintenance of which is comparatively inexpensive on account of the fastening means and the barrier itself being

submitted to great strains instead of sudden shocks, and one in which there is an equal distribution of the strain irrespective of the location along its length at which the 60 barrier is encountered by a moving vehicle.

The invention is adapted to be made in many different forms and in different sizes, and one swinging gate to cover a whole roadway or two swinging gates to abut in 65 the center of the roadway can be used, all such constructions being adapted for my improved means for minimizing the shock on the barrier.

For the purpose of clearly illustrating my 70 invention I show one embodiment of the invention in the accompanying drawing, in which Figure 1 is a face view of a swinging barrier and its pivotal support, said barrier being fastened at its free end at the 75 center of the roadway to a second swinging barrier, only the outer or swinging end of the latter, however, being shown. Fig. 2 is an enlarged view partly in section along line 2—2, in Fig. 1, to illustrate more in detail the construction of the form of barrier 80 shown. Figs. 3 and 4 are diagrammatic views showing how the barrier can become distorted by a strain put on it in the direction of traffic on the road that the barrier 85 blocks.

Many accidents, and some of them fatal, have resulted by reason of a vehicle, such as an automobile or the like, running into a gate that has been closed near an open draw, 90 or by running against a gate on a ferry boat. If the gate is fixed in position it sometimes is able to withstand the shock of the collision, but damage to the vehicle usually results and traffic is blocked. On the 95 other hand, if a rigid barrier with insecure fastening means is used, the barrier is either bent and twisted by the force of the collision, or the fastening means is broken, and in the latter event, all resistance to the vehicle gives way and if it has momentum enough it passes on through the gate and many fatal accidents have resulted from vehicles running into open draws, or off the 100 ends of ferry boats by reason of the breakage of such gates.

The form of gate shown is arranged to be swung to close the roadway 10 and it comprises a barrier 11 which is pivoted at one end as at 12, at its top and bottom portion, 110 to a standard 13, the details of such pivotal connection, however, being immaterial so

long as the gate can swing to an open and closed position, the form of gate illustrated also embodying a barrier similar to the barrier 11, such barrier 14 having only its outer 5 or swinging end illustrated, the ends of the barriers being joined in the center of the roadway by a connection that is preferably pivotal. The barrier is adapted to be distorted and is made of sections, and these sections 10 may be of the same length or of different lengths, the illustration showing two sections 15 and 16, the section 15 being longer than the section 16, the section 15 having the tubular part 17 and the section 16 having the 15 tubular part 18, these tubular parts being horizontal. These sections 17 and 18 are adapted to be moved apart longitudinally and also to swing pivotally on one another by reason of a pivotal and resilient connection between them. The sections abut at 20 their respective upright portions 19 and 20, these preferably being made of channel iron as shown in Fig. 2, and a chain 21 or any other similar strand passes through said 25 channel irons and into the tubular portions 17 and 18, the chains being provided on their ends with eye-bolts 22 and being provided on their ends with abutting or bearing elements, such as the collars 23. The collars 23 30 fit over the screw-threaded ends 24 of the eye-bolts 22 and are moved along on the threaded ends 24 by the nuts 25. When these nuts are screwed up so as to be moved toward each other, they act to compress the 35 springs 26, these springs abutting at one end on the collars 23 and on their inner ends against the thimbles 27 or any other suitable form of stop. The springs 26 thus have a 40 tendency to press the abutting parts 19 and 20 together and they thus normally hold the sections of the barrier in proper position and form a substantially stiff barrier which, under normal conditions, swings as a unit and provides a substantial closure for the roadway. It will be evident that other forms of 45 yielding and resilient means can be employed for holding these sections together, and I do not wish to be understood as limiting myself to the particular form herein 50 shown and described.

A pivotal connection for the end of the barrier is shown in Figs. 1 and 2 where the two barriers 11 and 14 are joined by a fastening comprising a bolt 28 which slides in 55 bearings 29 and which has hooked portions 30 fitting in the knuckles 31 so that when the bolt is down in the position shown in Fig. 1, the barriers 11 and 14 are held together, but with a pivotal movement between them, such 60 relative pivotal movement being due to the fact that the hooks 30 and the bolt 28 can turn in the bearings 29 and the knuckles 31 respectively. Suitable handles 32 are provided, these being preferably placed at a di- 65 vergent angle so that the bolt 28 can be oper-

ated from both sides of the gate and for the further reason that the handles do not interfere with the relative swinging of the sections, as will be hereinafter evident. The upward movement of the bolt is limited by 70 reason of the collar 33, by means of which the handles 32 are fastened to the bolt 28, engaging the upper edge 34 of a slot in a stiffener plate 35 in the end standard 36 of the barrier 14, when the bolt 28 is moved upward, the lower edge of said slot acting to limit the downward movement of the bolt to prevent the hooks 30 from entering too far into the knuckles 31.

The diagrammatic views of Figs. 3 and 4 80 illustrate how the gate yieldingly gives way to pressure due to contact by a moving vehicle with the barrier. In Fig. 3 I have shown in dotted outline the normal position of the gate when it is closed, the barriers 11 and 14 being substantially in line, and in full lines I show the gate in the position it would assume when a force is directed centrally on the gate, that is, in the center of the roadway where the barriers 11 and 14 85 come together, the chain 21 being illustrated to show how the sections are permitted to move from each other longitudinally by reason of the compression of the springs 26 and considerable movement of the gate can thus 90 be made possible since, with such two barriers installed in a roadway 40 feet wide and with springs about 4 feet long in each of the barrier sections 15 and 16, the movement of the center of the gate from the dotted to the 95 full line position in Fig. 3 will amount to about 11 feet, during which time the resistance to the passage of a vehicle colliding with the gate slowly increases, the strain on the parts is minimized and made gradual 100 and an ultimate stopping of the vehicle is 105 probable.

In Fig. 4 I show how the sections can be moved out of line and also extended longitudinally when the force exerted against the 110 gate is adjacent to one edge of the roadway, and with dimensions as hereinbefore set forth and with the gate distorted as shown in Fig. 4, the movement from the normal closed position of the gate to the point far- 115 ther from its normal position amounts to about 10 feet.

The number of sections to be employed in a barrier can be varied, they can be constructed in many different ways, and the fastening means employed at the ends of the barrier can be modified from those shown without departing from the scope of the invention as set forth in the claims.

Having thus described my invention, I 12 claim:

1. In a gate, a barrier, means for fastening the barrier in closed position, and a resilient means in said barrier for permitting both a limited lateral and extensible 13

movement of the barrier relative to the fastening means.

2. In a gate, a sectional barrier, means for fastening the barrier in closed position, said fastening means being pivotally connected to the barrier, and a yielding resilient connection between sections of the barrier to permit both extension and distortion of the barrier when a vehicle collides 10 with said barrier.

3. In a gate, a barrier, said barrier comprising sections connected by flexible resilient extensible connections, and means for fastening the ends of the barrier in closed 15 position.

4. In a gate, a barrier, said barrier comprising sections connected by flexible resilient extensible connections, and fastening means for pivotally fastening the ends of 20 the barrier when the barrier is in closed position.

5. In a gate, a barrier comprising sections adapted to be separated longitudinally and pivotally, a resilient flexible connection between the sections to permit such separation, and means for securing the barrier in 25 closed position.

6. In a gate, a barrier comprising sections adapted to be separated longitudinally and pivotally, flexible strands connecting said sections, and springs abutting on the strands and the sections for yieldingly holding the sections together.

7. In a gate, a barrier made up of sections 30 pivotally connected so that the barrier can be distorted and extended, and resilient connections between the sections to yieldingly resist such distortion and extension and to hold the sections in their normal relative 35 positions.

8. In a gate, a barrier made up of sections, resilient means for permitting longitudinal separation and pivotal movement between said sections whereby the barrier can be distorted, and means for pivotally fastening 45 the ends of the barrier in closed position.

9. In a gate, a barrier comprising sections connected by flexible and resilient means to

permit elongation and distortion of the barrier, means on one end of the barrier for 50 pivoting the barrier to a support, and a pivotal means for fastening the swinging end of the barrier.

10. In a gate, a barrier formed of sections, a flexible band connecting and extending within the limits of the sections, a spring abutting on the ends of the strand and on the adjacent ends of the sections, and means for pivotally fastening the ends of the barrier in an approximately fixed position. 60

11. In a gate, a swinging barrier comprising sections with tubular parts, a strand extending into the tubular parts, springs in the tubular parts, collars on the strand for engaging the outer ends of the springs, and 65 stops in the tubular parts against which the springs abut.

12. In a gate, a barrier made up of sections, the sections comprising tubular parts and abutting uprights, a chain passing into 70 the tubular parts, eye-bolts on the ends of the chain, collars adjustably arranged on the eye-bolts, and springs interposed between the collars and the uprights.

13. In a gate, barriers adapted to swing 75 to closed position with their outer ends adjacent to each other, the barriers being formed of sections with flexible resilient and yielding connections whereby the barriers are subject to distortion, and a fastening means connecting the barriers and forming pivotal connection between them.

14. In a gate, barriers adapted to swing to closed position with their outer ends adjacent to each other, the barriers being 85 formed of sections with flexible resilient and yielding connections whereby the barriers are subject to distortion, a sliding bolt on one barrier, said bolt having a hook thereon, and a knuckle on the second barrier to receive the hook.

In testimony that I claim the foregoing, I hereto set my hand, this 28th day of December, 1916.

MICHAEL LOPRETE.
